UNITED STATES PATENT OFFICE

OSCAR H. DICKE, OF ROCHESTER, NEW YORK, ASSIGNOR TO GENERAL RAILWAY SIGNAL COMPANY, OF ROCHESTER, NEW YORK

TRAIN-DISPATCHING SYSTEM FOR RAILROADS

Application filed April 13, 1929. Serial No. 354,881.

The present invention relates to train dispatching systems, and more particularly to synchronous selector control apparatus for controlling wayside signals of such dispatching system. In the prior application of Dicke and Hitchcock Ser. No. 346,731 filed March 13, 1929, ways and means have been shown whereby channel selecting relays at various way stations will be rendered active first at one way station, then at the next etc. In said prior application the control was transferred from one way to the next succeeding way station only after each of the channel selecting relays at such one way station had all been operated sequentially, the organization of circuits being such that a line relay at only one way station could be operated at one time.

In accordance with the present invention it is proposed to render the line relay at only one way station of a large number of way stations active at one time to control its associated channel selecting relays the line relays at all way stations functioning, but the circuits controlled thereby being rendered operable at one way station at a time only. Also in accordance with the present invention it is proposed not only to select the way stations one at a time, but it is proposed to select such way station distinctively and irrespective of channel selecting relay control and to interrupt all of the channel or message circuits at such way station separately by the way station selecting means at all other times except when such a way station is selected.

Another feature of the present invention resides in the provision of way station selecting means which require no additional line circuits or wires. Another feature of the present invention resides in a novel bank of channel selecting relays of the neutral type which channel selecting relays may be rendered operative one at a time sequentially for successively closing distinctive channel circuits.

Other objects, purposes and characteristic features of the present invention will appear as the description thereof progresses and will in part be obvious from the accompanying drawings.

In describing the invention in detail reference will be made to the accompanying drawings in which:

Fig. 1A shows the apparatus in the dispatcher's office of one system embodying the present invention; 55

Fig. 1B illustrates the apparatus at two successive way stations of the same system, so that Figs. 1A and 1B laid end to end constitute the complete system; 60

Fig. 2 shows the station selecting means of a modified system, the channel selecting relays and other features of this modified system being the same as that shown in Figs. 1A and 1B. 65

Referring first to Fig. 1B of the drawings, this figure shows one passing siding PS of a railway system having many such sidings as well as diverging routes, crossings, and alike, of which the remaining portion of the system has for convenience been omitted. The track switch at the east end of this passing siding PS is preferably operated by suitable power-operated means such as the switch machine SME, the switch at the west end being controlled by a similar switch machine SMW. The east end of this passing siding PS has associated therewith two starting signals 2 and 2^a, an entering signal 1 and a take siding 1^a, whereas the west end of this passing siding is provided with starting signals 7 and 7^a an entering signal 8 and a take siding signal 8^a. There is also provided a message wire over which the wayside signals and switch machines are controlled and indications are transmitted, a stepping wire whereby the various relays are controlled in step-by-step fashion in synchronism with relays in the dispatcher's office, and a common return wire, as well as a 60-cycle transmission line TL, extending through the entire railway system. 70

As will appear hereinafter, the switch machines and signals at many passing sidings may be controlled over these comparatively few line wires. 75

At each way station are employed a number of relays used for various purposes, and for convenience it is necessary only to mention the relays at the second way station, the corresponding relays of other way stations 80

being designated by like reference characters having distinctive exponents. At way station No. 2 are provided a signal relay CR^2 , a direction of travel relay DR^2 and a switch machine relay SMR^2 for the purpose of controlling the signals and switch machines located at that particular way station, a detector track relay DT being employed to indicate in the dispatcher's office the passage of a train by such way station. The way station selecting relays include a high frequency relay HFR^2 , a polar line relay LR^2 , a low frequency relay LFR^2 , and a repeater relay RR^2 , whereas the channel selecting relays of this particular way station have been designated E^2, F^2, G^2 , and H^2 .

Referring now to the dispatcher's office equipment (see Fig. 1A) wherein the railway system, to which the dispatching system embodying the present invention is applied, has been reproduced in miniature, of which the passing siding ps only has been illustrated. At the east end of this passing siding ps is provided an indicating lamp I^2 , which is illuminated in response to occupancy of the detector track circuit at the east end of the passing siding ps . Associated with the east end of this miniature passing siding ps , is a signal lever SL including the contact 9 and a switch machine lever SML , these levers SL and SML controlling the relays CR^2, DR^2 , and SMR^2 through the medium of the synchronous selector system in a manner as more clearly described hereinafter.

The dispatcher's office equipment also includes commutator apparatus including the rotatable arm 10, which is rotated through the medium of suitable means such as a direct current motor M , and a high frequency generator HFG , as well as a source of 60-cycle alternating current illustrated by the transformer 12. The dispatcher's office equipment also includes a high frequency relay HFR^0 , polar line relay LR^0 , and a series of way station selecting relays SR^1, SR^2, SR^3 , and SR^4 . Each of these way station selecting relays is adapted to connect the line relay LR^0 to a particular group of channel selecting relays. The channel selecting relays for the way station selecting relay SR^1 being designated A, B, C, and D, the channel selecting relays for the way station selecting relay SR^2 being designated E, F, G, and H and the channel selecting relay for the way station selecting relay SR^3 being designated I, J, K, and L.

The stepping line heretofore mentioned is also used as a transfer line, in that the control is transferred from one way station to another through the medium of alternating current superimposed on this same stepping line. It will be noted that adjacent to each line relay there is contained in series with the stepping circuit an inductive reactance 15, containing an exponent corresponding to the exponent of the associated relay, and

bridged around this line relay and reactance is a tuned unit comprising an inductance 16 and a condenser 17 having the proper exponents, this tuned unit being tuned to resonate to the high frequency of the generator HFG , so that this high frequency readily flows around the line relay LR . It will be noted that the high frequency relays HFR are connected in multiple between the stepping line and the common return wire C through a condenser 18, these condensers being so small as not to allow the 60-cycle current to flow freely therethrough, and of course blocking the flow of direct current. In addition to the high frequency relay HFR having an exponent corresponding to the station there is a low frequency relay LFR having a similar exponent for each way station, these low frequency relays being picked up through a circuit connecting such relay with the next preceding way station, through the medium of the same stepping line as will more clearly appear hereinafter. It may be pointed out here that the circuits for carrying the low frequency 60-cycle current to these low frequency relays LFR having suitable exponents include units resonated to this 60-cycle frequency, the first of which comprises condenser 37 and inductance 38, the second unit comprises condenser 39 and inductance 40 and the third unit comprises condenser 41 and inductance 42, each of these reference numbers having an exponent corresponding to the particular way station at which they are located.

With this apparatus in mind, it is believed that the detail construction of the system, as well as its operating characteristics and features, are best understood by considering the operation of the system.

Operation.—Let us assume that the motor M is started by connecting it to its source of current, such as the battery 43, shown through a suitable switch 44, thereby causing the contact arm 10 to be rotated in a clockwise direction. When the arm 10 engages the contact 21, the bridging contact 45 engages the stationary contacts 46 and 47, so that simultaneously there are completed two alternating current circuits one including a high frequency source HFG and the other including the low frequency 60-cycle source 12. The first or high frequency circuit may be traced as follows:—beginning at the generator HFG blocking and tuning condenser 48, wires 49, 50, and 51, stationary contact 21, contact arm 10, wire 52 to the stepping line over which the high frequency may readily flow by reason of the tuned units 16-17, having exponents corresponding to the way station at which they are located, which units are tuned to resonate to the high frequency, and from whence the circuits divided through the high frequency relays HFR, HFR^1, HFR^2 , etc., through their associated condensers 18¹, 18², 18³, etc., to common return 130

wire C connected to the other side of high frequency generator HFG. The second or low frequency circuit may be traced as follows:—beginning at the secondary winding 5 of the transformer 11, condenser 6, wire 55, contacts 46—45—47, wire 56, from whence the circuit divides through the upper winding of the relay SR¹ through condenser 57, back to the transformer 11, and through wire 58, the stepping wire to the first way station, the wire 59, front contact 60 of the high frequency relay HFR¹, wire 61, contact 62 of line relay LR' in its left hand position, wires 63 and 64, winding of the low frequency relay LFR¹, wire 65, condenser 41¹, inductance 42¹, to the common return wire C back to the transformer 11. Attention is directed to the fact that there is no circuit relay for LFR² at this time because the contact 108 of relay LR² is to the left.

The first or high frequency circuit picks up the station selecting relay SR¹, the upper winding being designed for high frequency alternating current, in the dispatcher's office, which relay is then stuck up through the following circuit:—beginning at the terminal B of a suitable battery, back contact 66 of the relay SR⁴, wire 67, back contact 68 of the relay SR³, wire 69, back contact 70 of the relay SR², wire 71, stick contact 72 of the relay SR¹ through the lower winding of this relay SR¹ to the wire C connected to the other terminal of said battery. With the relay SR¹ energized it will be noted that current may flow from the contact 73 of the line relay LR⁰ through contact 74 and 75 of relay SR¹ to the channel selecting relays A, B, C, and D located in the dispatcher's office.

Similarly, as the rotating arm 10 advances a little further, the high frequency relay HFR¹ at the way station No. 1 is de-energized, causing completion of a stick circuit for the low frequency relay LFR¹, which may be traced as follows:—starting at the secondary winding 77 of the transformer 78, wires 79, back contact 80 of the relay HFR¹, wire 81, stick contact 82 of the low frequency relay LFR¹, wires 83 and 64, winding of this low frequency relay LFR¹, wires 65, condenser 41¹, inductance 42¹, common return wire C, inductance 38¹, condenser 37¹, back to the secondary winding 77. It is thus seen that the low frequency relay LFR¹ is stuck up through the medium of its contact 85 and allows the channel selecting relays at the way station No. 1 to be controlled through the medium of the contact 86 of the line relay LR¹, in a manner as hereinafter more clearly explained in connection with way station 2. Obviously, if the contact arm 10 is rotated to the right, and successively engages the stationary contacts 22 to 26 inclusive the line relays LR⁰, LR¹, and LR² are repeatedly operated to their two polar positions thus

causing the channel selecting relays A, B, C, and D, and the corresponding channel selecting relays (not shown) at station 1 to be operated sequentially and in synchronism.

Let us now see how the control in the dispatcher's office is transferred from the group of channel selecting relays A, B, C, and D to the group of channel selecting relays E, F, G, and H, and see how the control is transferred from the way station No. 1 which way station is effective because its low frequency relay LFR¹ is energized, is transferred to the way station No. 2 by energizing the low frequency relay LFR², and simultaneously therewith de-energizing the low frequency LFR¹.

Since the stepping current applied to the line relays LR⁰, LR¹, and LR² from the battery 44 through the medium of inductance 54, consists of a series of 5 impulses, the first of which was positive and the last of which was positive, leaves the line relays LR⁰, LR¹, and LR² all in their right hand position, these line relays being of the direct current permanent magnet stick type, so that if operated to a particular position the contacts thereof will remain in such position in spite of de-energization of its winding until the relay has been energized by current of the reverse polarity.

With these line relays assuming their right hand position and the contact arm 10 engaging the stationary contact 27, the high frequency relays HFR⁰, HFR¹, and HFR² will be energized. Energization of the high frequency relay HFR⁰, effects energization of the relay SR² through the following circuit:—beginning at the terminal B of a suitable battery, front contact 90 of the relay HFR⁰, wire 91, contact 92 of the line relay LR⁰ assuming its right hand position, wires 93 and 94, front contact 95 of the relay SR¹, wires 96 and 97, winding of the relay SR², to common return wire C connected to the other terminal of said battery. As soon as the relay SR² picks up it is stuck up through the following circuit:—beginning at the terminal B of said battery, back contact 66, of the relay SR⁴, wire 67, back contact 68 of the relay SR³, wires 69 and 98, stick contact 99 of the relay SR², wire 97, winding of the relay SR² to common return wire C. As soon as this relay SR² picks up, the relay SR¹ is de-energized because its stick circuit is broken at the back contact 70 of the relay SR².

Let us now see how momentary energization of the high frequency relays HFR¹ and HFR² causes the station selection low frequency relay LFR² to be energized and the station selecting relay LFR¹ to be de-energized, remembering that the line relays LR¹ and LR² now assume their right hand position, and bearing in mind that the repeater relay RR¹ which is a slow-dropping relay is

energized through the front contact 85 of the relay LFR^1 . As the high frequency relay HFR^1 and HFR^2 pick up the low frequency relay LFR^1 is de-energized because its stick circuit is broken at the back contact 80 of the relay HFR^1 . Since, however, the repeater RR^1 is slow-dropping the low frequency relay LFR^2 at the way station 2 is picked up through the following circuit before the repeater relay RR^1 drops:—beginning at the secondary winding 101 of the transformer 78, wire 102, front contact 103 of the repeater relay RR^1 , wire 104, stepping line, it being noted that the alternating current is blocked in both directions by the line relays LR^1 , LR^2 having in multiple therewith a unit resonated to high frequency which blocks the flow of low frequency current, wire 105, front contact 106 of the relay HFR^2 , wire 107, contact 108 of the relay LR^2 assuming its right hand position, wires 109 and 110, relay LFR^2 , wire 111 condenser 41², inductance 42², common return wire, inductance 40¹, condenser 39¹, back to the secondary winding 101 of the transformer 78.

As soon as the way station selecting relay LFR^2 is energized, bearing in mind that the high frequency relay HFR^2 is immediately de-energized, causes the following stick circuit for this relay LFR^2 to be completed:—beginning at the secondary winding 113 of the transformer 114, wire 115, back contact 116 of the relay HFR^2 , wire 117, front stick contact 118, of the relay LFR^2 , wires 119 and 110, winding of the relay LFR^2 , wire 111, condenser 41², inductance 42², common wire C, inductance 38², condenser 37², wire 120, back to secondary winding 113.

The way station selecting relay LFR^2 is now energized and all other low frequency way station selecting relays are de-energized, so that the only channel selecting relays which are operated at any of the way stations are those located at way station No. 2, these channel selecting relays being controlled through the medium of the front contact 121 of the relay LFR^2 , as will directly appear. In this connection it should be remembered that in the dispatcher's office the only one of the SR relays energized is the relay SR^2 , and this relay SR^2 through the medium of contacts 122, 123, and 124 conditions the channel selecting relays E, F, G, and H for operation in synchronism with the channel selecting relays E^2 , F^2 , G^2 , and H^2 located at the way station No. 2.

Let us now observe how these two groups of channel selecting relays are operated sequentially and relays of like reference letter are operated in synchronism. When the contact arm 10 engages the stationary contact 28 direct current of negative polarity is applied to the line circuit thus operating the line relays LR^0 , LR^1 , and LR^2 to their left hand position. With the contact 73 of

the line relay LR^0 in its left hand position, and with the selecting relay SR^2 energized, the channel selecting relay E is energized through the following circuit:—beginning at the terminal B of a suitable battery, contact 73 of the relay LR^0 in its left hand position, wires 126, 127, and 128, front contact 123 of the relay SR^2 , wires 129 and 196, contact 197 of relay F, wire 130, winding of the channel selecting relay E, wire 131, back contact 132 of the channel selecting relay F, wires 133 and 134, back contact 135 of the relay G, wires 136 and 137, back contact 138 of the relay H to common return wire C connected to the other terminal of said battery.

Similarly, the corresponding channel selecting relay E^2 is energized simultaneously with the energization of the relay E through the following circuit:—beginning at the terminal B, front contact 121, of the relay LFR^2 , wires 140 and 141, polar contact 142 of the relay LR^2 assuming its left hand position, wires 143, contact 204 of relay F^2 , wires 144 and 168 winding of the channel selecting relay E^2 , wire 145, back contact 146 of the channel selecting relay F^2 , wires 147 and 148, back contact 149 of the relay G^2 , wires 150 and 151, back contact 152 of the relay H^2 to common return wire C connected to the other terminal of said battery. The channel selecting relays E and E^2 are thus energized simultaneously and message circuit including front contacts of these relays may connect suitable apparatus at way station No. 2 and suitable apparatus in the dispatcher's office, in a manner as more clearly described hereinafter. It should be noted that the relays E and E^2 are stuck up through the following stick circuits, respectively, as soon as they assume their energized condition:—(1) B, wire 158, stick contact 159, wire 160, winding of relay E, 131, 132, 133, 134, 135, 136, 137, and 138 to C; and (2) B, 165, 166, 167, 168, winding of the relay E^2 , 145, 146, 147, 148, 149, 150, 151, and 152 to C.

Let us now observe how the movement of the contact arm 10 of the dispatcher's office into contacting relationship with stationary contact 29 causes the relays F and F^2 to be picked up simultaneously. This shifting of the contact 10 applies current of the positive polarity to the line circuit thus operating the line relays LR^0 , LR^1 and LR^2 to the right. Also, not only are the relays E and E^2 held up through a stick circuit, but the relays F and F^2 are picked up. The pick up circuit for the relay F may be traced as follows:—beginning at the terminal B, contact 73 of the relay LR^0 to the right, wires 155 and 156, contact 122 of the relay SR^2 , wires 157, and 170, front contact 171 of the relay E, wires 172 and 173, winding of the relay F, wires 174 and 134, back contact 135 of the relay G, wires 136 and 137, back contact 138 of the relay H to common return wire C connected to the other terminal of said battery. It will be noted that

with the relay F picked up the energizing and stick circuits for the relay E are broken at the back contact 132 of the relay F causing the relay E to assume its de-energized position.

Similarly, with the line relay LR² moved to the right pick-up circuit is completed for the channel selecting relay F² which may be traced as follows:—beginning at the terminal B, front contact 121 of the relay LFR², wires 140 and 141, contact 142 of the relay LR² assuming its right hand position, wires 163 and 164, front contact 177 of the relay E², wires 178 and 179, winding of the relay F², wires 180 and 148, back contact 149 of the relay G², wires 150 and 151, back contact 152 of the relay H², to common return wire C. Also, picking up of the channel selecting relay F² breaks the energizing and stick circuits of the channel selecting relay E² by opening its back contact 146, so that now only the channel selecting relays F and F² are energized and control channels may be completed through front contacts of these channel selecting relays.

The relays F and F² are now stuck up through the following stick circuits:—(1) B, 185, 186, 187, 173, winding of relay F, 174, 134, 135, 136, 137, 138, and (2) B, 190, 191, 192, 179, winding of the relay F², 180, 148, 149, 150, 151, 152, to common return wire C.

Movement of the contact arm 10 into engagement with the stationary contact 30 effects operation of the line relays LR⁰, LR¹, etc. to the left thereby causing closure of the following pick-up circuits for the relays G and G² (1) beginning at the terminal B, contact 73 of the line relay LR⁰ to the left, 126, 127, 128, 123, 129, 196, 197, 198, 199, winding of the relay G, 200, 137 and 138, to common return wire C; and (2) beginning at the terminal B, front contact 121 of the relay LFR², 140, 141, contact 142 to the left, 143, 204, 205, 206 winding of the relays G², 207, 151 and 152, to common return wire C.

With the relays G and G² energized the following stick circuits for these relays are closed:—(1) beginning at the terminal B, wire 211, contact 212, wires 213 and 199, winding of the relay G, wires 200, 137 and 138, to common return wire C; and, (2) beginning at the terminal B, wire 215, contact 216, wires 217 and 206, winding of the relay G², wires 207, 151 and 152 to common return wire C. The relays G and G² are thus stuck up.

As the rotating contact arm 10 moves to the next stationary contact 31 the various line relay LR⁰, LR¹, and LR² are moved to their right hand position thereby completing the following pick up circuits for the relays H and H², respectively:—(1) terminal B, contact 73 of the line relay LR⁰ to the right 155, 156, 122, 157, 210, 221, 222, 223,

224, winding of the relay H, 225, to common return wire C; and, (2) beginning at the terminal B, front contact 121 of the relay LFR², 140, 141, contact 142 in its right hand position, 163, 214, 236, 237, 238, 230, winding of the relay H², wire 231, to common return wire C. The relays H and H² are thus simultaneously energized to complete suitable channel circuits as more clearly described hereinafter. Also, picking up of relays H and H² breaks the stick circuits of relay G and G² at back contacts 138 and 152, respectively.

With the relays H and H² now energized the following stick circuits for these relays are closed:—(1) beginning at the terminal B, contact 73 to the right, 155, 156, 122, wires 157, 210 and 232, stick contact 233 of the relay H, wires 234 and 224, winding of the relay H, wire 225, to common return wire C, and (2) beginning at the terminal B, contact 121 of the relay LFR², wires 140 and 141, contact 142 to the right, wires 163, 214 and 236, front stick contact 237 of the relay H², wires 238 and 230, winding of the relay H², wire 231, to common return wire C. If the rotating contact arm now engages the next stationary contact 32, the line relays LR⁰, LR¹, and LR² are moved to the left, thereby de-energizing the relays H and H², because their stick circuits include the right hand contacts of these line relays LR⁰ and LR².

As the rotating contact arm 10 engages the next and longer stationary contact 33, high frequency current will be applied to the stepping line thereby energizing the high frequency relays HFR⁰, HFR¹ and HFR². Since the line relay LR⁰ now assumes the left hand position, it having assumed the right hand position the last time the high frequency relay HFR⁰ was energized, the control will be transferred from the relay SR² to the relay SR³, in that the following pick-up circuit for the relay SR³ is closed:—beginning at the terminal B, front contact 90 of the relay HFR⁰, wire 91, contact 92 of the relay LR⁰ to the left, wire 240, front contact 241 of the relay SR², wires 242 and 243, winding of the relay SR³ to common return wire C. As soon as this relay SR³ is energized, the following stick circuit therefore is closed:—beginning at the terminal B, back contact 66 of the relay SR⁴, wires 67 and 244, front stick contact 245 of the relay SR³, wires 246 and 243, winding of the relay SR³, to common return wire C. With the relay SR³ now energized the stick circuit for the relay SR² is broken at the back contact 68 of the relay SR³, so that the relays I, J, K, and L, the circuits of which have for convenience been omitted, may be controlled by the line relay LR⁰ through front contacts 247 and 248 of relay SR³.

Simultaneously with the shifting of the

control from the front contacts of relay SR^2 to the front contacts of relay SR^3 the control is transferred from contacts of the relay LFR^2 to contacts of the relay LFR^3 (not shown). This shifting of the control from the way station No. 2 to way station No. 3 through contact 103² of the relay RR^2 is accomplished in a manner as explained in connection with the contact 103 of the relay RR^1 .
 10 As just mentioned the high frequency relay HFR^2 is now energized because the rotating contact arm 10 engages the stationary contact 33, from which it appears that back contact 116 of the relay HFR^2 is picked up, thereby opening the stick circuit for the relay LFR^2 , bearing in mind that the pick-up circuit for this relay LFR^2 is now open because the contact 108 of the relay LR^2 is now to the left. It is thus seen how the control may be shifted from one way station to another, and simultaneously will be shifted from one group of channel selecting relays to another in the dispatcher's office.
 15

Reviewing this matter briefly, the relays 25 A, B, C, D, E, F, G, H, I, J, K, and L will be successively energized one at a time and simultaneously with each energization of a relay there will be energized a corresponding relay at one of the way stations, this corresponding relay having the same reference letter having a distinctive exponent corresponding to the number of the way station applied thereto. Of these way station relays the relays E^2 , F^2 , G^2 and H^2 only have been 30 illustrated. In practice, there will be a sufficient number of stationary contacts engageable by the rotating contact arm 10 to take care of all the station selecting relays and channel selecting relays of the system, and these stationary contacts will be spaced around the entire circumference through which the contact arm 10 rotates. From this it appears that each time that the contact arm 10 starts upon a new revolution, the channel 35 selecting relay system will be started on a new cycle of operation through the medium of contacts 46, 45 and 47.

As already mentioned it is proposed to carry channel circuits through front contacts 50 of corresponding channel selecting relays, so that a large number of distinctive control circuits are sequentially set up each of which includes the same message line wire. It readily appears that should one of these channel selecting relays be energized, or its front contacts remain closed for some reason or another, that one of the channel branches might be held closed continuously thereby setting up false indication and control circuits, were it 55 not for the fact that the channel circuits, as hereinafter explained are also carried through front contacts of the way station selecting relays, such as, relay LFR^2 , and similarly these message circuits are carried 60 through front contacts of the dispatcher's se-

lecting relay such as SR^2 . In other words, the message line circuit by the selection of a particular way station is continued through this way station so long as this way station is selected, it being carried through the particular channel selecting relay of such way station so long as such particular channel selecting relay is energized, from which it appears that a wrong channel or message circuit could not be set up unless there were two failures, one of which resided in the unauthorized closing of a way station selecting relay contact and the other of which resided in the unauthorized closing of the contact of a channel selecting relay.
 70

Also, it will be noted that if one of the channel selecting relays should get out of step, as in response to an impulse due to a lightning discharge or the like, that these channel selecting relays will be resynchronized and brought back into step in the next following cycle, this because the channel selecting relays are initiated in response to the first impulse of proper polarity as the particular way station has been selected, so that they are necessarily resynchronized. Also, the selection of a particular way station at the proper point during the rotation of the contact arm 10 is assured, even though such way station selection should get out of step falsely as by a lightning impulse, or the like, in that at the end of the cycle of operation the various high frequency relays HFR^1 , HFR^2 , etc. are energized several times by the contact arm 10 engaging the stationary resynchronizing contacts 250 and 251, from which it appears that if a way station is still selected when contact arm 10 reaches contact 250 it will be brought back in step by being cut out, so that at the beginning of the next cycle, the way station No. 1 will be selected at the proper time, namely when the contact arm 10 engages the stationary contact 21.
 80

Let us now observe the operation of the system and see how operation of the switch machine lever SML in the dispatcher's office will cause operation of the switch machine SME located at way station No. 2. Let us assume that the lever SML is moved to its left hand dotted position, under which condition when the way station No. 2 has been selected and the relays H and H^2 are simultaneously energized, the following circuit for the switch machine relay SMR^2 is momentarily closed thus operating the relay SMR to the left:—beginning at the terminal B minus of the battery 252, contact of lever SML , wire 253, contact 254 of the relay H , wire 255, back contact 256 of the relay G , wire 257, back contact 258 of the relay F , wire 259, back contact 260 of relay E , wire 261, front contact 124 of relay SR^2 , wire 262, message line wire, wire 263, front contact 264 of the relay LFR^2 , wire 265, back contact 266, of the relay E^2 , wire 267, back contact 268 of the 90

130

relay F^2 , wire 269, back contact 270 of the relay G^2 , wire 271, front contact 272 of the relay H^2 , wire 273, winding of the relay SMR^2 , wires 274, 275 and 276, to common return wire C connected to the mid point of battery 252. The switch machine relay SMR is thus operated to its left hand dotted position, and in turn through suitable circuits as more fully described in the prior application 10 of S. N. Wight, Ser. No. 326,185, filed November 22, 1928, operates the switch machine SME to its take-siding position.

Similarly, movement of the signal lever SL to its right-hand position will clear an east bound signal by reason of the application of positive polarity to each of the following message circuits, which are closed sequentially as the relays F and G assume their energized positions sequentially:—(1) beginning at the positive terminal of battery 252, contact 9 of lever SL in its right-hand position, wire 280, contact 258 of relay F in its raised position, wire 259, contact 260, wire 261, contact 124, wire 262, message wire, wire 263, contact 264 of relay LFR^2 , wire 265, contact 266 of relay E^2 , wire 267, contact 268 of relay F^2 in its raised position, wire 281, winding of the relay CR^2 , wires 282 and 276, to common return wire C connected to the mid point of battery 252; and (2) beginning at the positive terminal of battery 252, lever SL in its right-hand position, wire 283, contact 256 of relay G in its raised position, wire 257, contact 258 of relay F in its lower position, wire 259, contact 260 of relay E , wire 261, contact 124, wire 262, message wire, wire 263, contact 264 of way station selecting relay LFR^2 , wire 265, contact 266 of relay E^2 in its lower position, wire 267, contact 268 in its lower position, wire 269, contact 270 of relay G^2 in its raised position, wire 284, winding of the relay DR^2 , wires 285, 275, and 276, to common return wire C connected to the mid point of said battery 252. With the relays CR^2 and DR^2 assuming their right hand position, and with the switch machine SME assuming its take-siding position traffic is set up for east bound movement off of the siding through the medium of the clearing of signal 2^a.

Similarly, if the detector track relay DT is deenergized in response to the passage of a train thereover, the following circuit is momentarily closed through each cycle of operation of the synchronous selector system:—beginning at the negative terminal of the battery 287, contact 288 of the track relay DT in its retracted position, wire 289, contact 266 of relay E^2 in its raised position, wire 265, contact 264, wire 263, message line, wire 262, front contact 124 of relay SR^2 , wire 261, contact 260 of relay E in its raised position, wire 290, winding of the indicating relay IR , wire 291, common return wire C, wire 292, to the mid point of battery 287. The comple-

tion of this circuit causes the indicating relay IR , which is a relay of the permanent magnet stick type, to be operated to its left hand position, whereby an energizing circuit for the indicating lamp I^2 is closed, thereby illuminating this lamp I^2 and informing the dispatcher that the detector track circuit at the east end of the passing siding PS is occupied.

Applicant has thus disclosed a train dispatching system of the synchronous selector counting relay type, in which one way station after another is selected sequentially through the medium of the same stepping circuit which controls the channel selecting relays, so that only 3 line wires including a common return wire are required, this on the assumption that there is already a 60-cycle source of current available at each way station. If no reliable 60-cycle source of current is available so a local source of distinctive alternating current may be provided from battery driven generators or tuned vibrating circuit interrupters instead of the transformers 11, 78, and 114. Also, attention is directed to the fact that not only are the way station channel selecting relays resynchronized with the way station selecting relays, but the way station selecting relays are resynchronized with the dispatcher's office equipment at the end of each cycle of operation of the system all in a manner as heretofore explained.

Modified construction.—Instead of passing the control from one way station to the next way station by the provision of the chokes or inductances 15¹, 15², etc., these chokes may be omitted and the control may be transferred from one way station to the next way station through the medium of a separate wire 300 as shown in Fig. 2 of the drawings. Also, instead of connecting the various high frequency relays HF , HFR^2 , etc. in multiple as illustrated in Fig. 1B of the drawings, these relays HFR^1 and HFR^2 will be connected in series as illustrated in Fig. 2 of the drawings, each of these relays HFR^1 and HFR^2 (see Fig. 2) being connected in multiple with its associated line relay LR^1 or LR^2 , as shown in Fig. 2 of the drawings. In this connection it is desired to point out that the high frequency relay HFR^1 and HFR^2 shown in Fig. 2 of the drawings are connected in series with an inductance 301¹ and 301² and a condenser 302¹ and 302², respectively, the constants of these relay inductances and condensers being such that each group is tuned to resonate at the high frequency, the inductance of the line relay LR^1 being sufficient to prevent the flow of high frequency current therethrough and with the high frequency relays tuned, as just explained, substantially all of the high frequency current will flow through the high frequency relays. Similarly, since the condensers 302¹ and 302² are respectively

180 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965

connected in multiple with the line relays LR¹ and LR² (see Fig. 2) all of the direct current will flow through these line relays LR¹ and LR². The arrangements for transferring the control from one way station to another is carried on in the arrangement shown in Fig. 2 of the drawings by relays DCR¹ and DCR² instead of relays LFR¹ and LFR², and in exactly the same way as in Fig. 1B of the drawings, except that separate line wires 300¹, 300² are used instead of superimposing low frequency current directly on the stepping circuit as is done in Fig. 1B of the drawings, a direct current source being used for these DCR¹ and DCR² as indicated by the terminal B and C in Fig. 2 of the drawings, instead of alternating current. In this connection it should be noted that there is a slight difference in the transfer circuit arrangements at the way station No. 1 as compared with way station No. 2, in that the direct current selecting relay DCR¹ is picked up only when the line relay LR¹ is to the right, whereas the direct current station selecting relay DCR² is picked up only when the corresponding line relay LR² is to the left. In other words, all of the stations having an odd number assigned thereto are selected when the line relays are in their right hand position, and all way stations having an even number assigned thereto are selected when the line relays assume their left hand position, this principle is taken advantage of in order to avoid the selection of more than one way station at a time. Obviously, instead of connecting the high frequency relays HFR¹, etc. of Fig. 1B in multiple they may be connected in series in a manner as shown in Fig. 2, if desired. In view of the great similarities between the way station selecting circuits shown in Fig. 2 of the drawings to that shown in Fig. 1B, and because the operating characteristics and principles are the same, it is believed unnecessary to specifically describe the operation of the modified construction shown in Fig. 2.

Having thus shown and described several embodiments of the present invention and having shown a rather specific circuit arrangement for carrying out this invention, it is desired to be understood that the particular circuit arrangements selected have been selected for the purpose of facilitating a description of the underlying principles of the invention as well as its operating characteristics and features, and not with the intent of showing the scope of the invention or the exact construction preferably employed in practicing the same, and that various additions, modifications, and alterations may be made to adapt the invention to the particular problem encountered in practicing the same, all without departing from the spirit or scope of the invention or the idea of means underlying the same, except as

demanded by the scope of the following claims.

What I claim as new is:—

1. In a synchronous selector system for controlling railway traffic controlling devices; the combination with a line circuit including a plurality of line relays in series; separate circuit selecting devices controlled by said line relays, and means for rendering only one of said circuit selecting devices responsive to its associated relay at one time comprising; a link circuit extending from one way station to another, and means for transferring the control from a previously responsive way station to the next adjacent way station including said link circuit and a contact of one of said line relays. 70 75

2. In a synchronous selector system for controlling railway traffic controlling devices; the combination with a line circuit including a plurality of line relays in series; separate circuit selecting devices controlled by said line relays, and means for rendering only one of said circuit selecting devices responsive to its associated relay at one time comprising; a link circuit extending from one way station to another, and means for transferring the control from a previously responsive way station to the next adjacent way station including said link circuit and a contact of one of said line relays. 80 85 90

3. In a synchronous selector system for controlling railway traffic controlling devices; the combination with a line circuit including a plurality of line relays in series; separate circuit selecting devices controlled by said line relays, and means for rendering only one of said circuit selecting devices responsive to its associated relay at one time comprising; a link line wire for each way station extending from such way station to the next preceding way station, a way station selecting relay, a transfer relay, a pick-up circuit for said way station selecting relay including said link line wire, a contact of the way station selecting relay of the next preceding way station, a contact of a line relay and a contact of said transfer relay. 100 105 110 115

4. In a synchronous selector system for controlling railway traffic controlling devices; the combination with a line circuit including a plurality of line relays in series; separate circuit selecting devices controlled by said line relays, and means for rendering only one of said circuit selecting devices responsive to its associated relay at one time comprising; a link line wire for each way station extending from such way station to the next preceding way station, a way station selecting relay, a transfer relay, a pick-up circuit for said way station selecting relay including said link line wire, a contact of the way station selecting relay of 120 125 130

the next preceding way station, a contact of a line relay closed only when said line relay assumes one of its two positions and a contact of said transfer relay, a pick-up circuit for the next adjacent way station selecting relay including the same wires and contacts of such next way station as the aforementioned pick-up circuit except that the contact of the line relay is one closed only when such line relay assumes the other of its two positions; whereby it is impossible to pick up several way station selecting relays successively without changing the positions of said line relays.

5. In a train dispatching system of the synchronous selector type; the combination with a stepping wire, a message wire and a common return wire connecting the dispatcher's office and each of a plurality of way stations; of a line relay and a transfer relay at the dispatcher's office and at each way station operated distinctively by the flow of currents over said stepping wire, a way station selecting relay at each way station, means for energizing one of said way station relays by current distinctive from the aforesaid distinctive currents over that portion of said stepping wire connecting said one relay with the next preceding way station, synchronous selector means controlled by said line relays, and way side signals controlled by said synchronous selector means over said message wire.

6. In a train dispatching system of synchronous selector type; the combination with a stepping wire, a message wire and a common return wire connecting the dispatcher's office and each of a plurality of way stations; of a line relay and a transfer relay at each way station operated respectively by the flow of distinctive direct and alternating currents over said stepping wire, a way station selecting relay at each way station, means for energizing one of said way station relays by current distinctive from the aforesaid distinctive currents over that portion of said stepping wire connecting said one relay with the next preceding way station, synchronous selector means controlled by said line relays, and way side signals controlled by said synchronous selector means over said message wire.

7. In a synchronous selector system for controlling railway traffic controlling devices; the combination with a stepping wire, a message wire and a common return wire connecting a dispatcher's office and a plurality of way stations; a separate multiple channel synchronous way station selector at each way station; station selecting means for selecting only one of said way station selectors controlled over said stepping and common wire, a circuit for operating the selected way station synchronous selector including said stepping wire and common wire, and a

master synchronous selector means in said dispatcher's office operated in synchronism successively with the various way station synchronous selectors.

8. In a synchronous selector system for controlling railway traffic controlling devices; the combination with a stepping wire, a message wire and a common return wire connecting a dispatcher's office and a plurality of way stations, a separate multiple channel synchronous selector at each way station; station selecting means for selecting only one of said way station selectors controlled by alternating current flowing over said stepping and common wire, a circuit for operating by direct current the selected way station synchronous selector including said stepping wire and common wire, and a master synchronous selector means in said dispatcher's office operated in synchronism successively with the various way station synchronous selectors.

9. A synchronous selector of the stepping relay type comprising; a line relay; a plurality of channel selecting relays arranged in order; a pick-up circuit for each odd numbered channel selecting relay including a front contact of the next preceding channel selecting relay, a back contact of the next succeeding channel selecting relay and a contact of said line relay closed when it assumes one extreme position; a pick-up circuit for each even numbered channel selecting relay including a front contact of the next preceding channel selecting relay, a back contact of the next succeeding channel selecting relay and a contact of said line relay closed when it assumes one extreme position; a pick-up circuit for each odd numbered channel selecting relay including a front contact of the next preceding channel selecting relay, a back contact of the next succeeding channel selecting relay and a contact of said line relay closed when it assumes one extreme position; and a stick circuit for each channel selecting relay including a back contact of the next succeeding channel selecting relay.

10. A synchronous selector of the stepping relay type comprising; a line relay; a plurality of channel selecting relays arranged in order; a pick-up circuit for each odd numbered channel selecting relay including a front contact of the next preceding channel selecting relay, and a contact of said line relay closed when it assumes one extreme position; a pick-up circuit for each even numbered channel selecting relay including a front contact of the next preceding channel selecting relay, and a contact of the next preceding channel selecting relay, and a contact of said line relay closed when it assumes the other extreme position; and a stick circuit for each channel selecting relay including a back contact of the next succeeding channel selecting relay.

11. A synchronous selector of the counting relay type comprising; a line relay; a plurality of channel selecting relays arranged in order; a pick-up circuit for each odd numbered channel selecting relay including a

front contact of the next preceding channel selecting relay, and a contact of said line relay closed when it assumes one extreme position; a pick-up circuit for each even numbered channel selecting relay including a front contact of the next preceding channel selecting relay, and a contact of said line relay closed when it assumes the other extreme position; and a stick circuit for each channel selecting relay including its own front contact and a contact opened upon the next change in the position of said line relay.

12. A synchronous selector of the counting relay type comprising; a polar line relay; a plurality of channel selecting relays arranged in order; a pick-up circuit for each odd numbered channel selecting relay including a front contact of the next preceding channel selecting relay and a contact of said line relay closed when it assumes one polar position; a pick-up circuit for each even numbered channel selecting relay including a front contact of the next preceding channel selecting relay and a contact of said line relay closed when it assumes the other polar position; and a stick circuit for each channel selecting relay including a back contact of the next succeeding channel selecting relay.

13. A synchronous selector of the counting relay type comprising; a polar line relay; a plurality of channel selecting relays arranged in order; a pick-up circuit for each odd numbered channel selecting relay including a front contact of the next preceding channel selecting relay and a contact of the next preceding channel selecting relay and a contact of said line relay closed when it assumes one polar position; a pick-up circuit for each even numbered channel selecting relay including a front contact of the next preceding channel selecting relay and a contact of said line relay closed when it assumes the other polar position; and a stick circuit for each channel selecting relay including its own front contact and a contact opened upon the next change in the position of said line relay.

14. In a synchronous selector train dispatching system, the combination with a bank of neutral channel selecting relays in a dispatcher's office, another neutral bank of channel selecting relays at a way station, of a stepping circuit including a line relay at the dispatcher's office and a line relay at said way station, an organization of circuits and contacts of said relays at said dispatcher's office and at said way station for causing simultaneous energization of the first relay of the neutral bank at said dispatcher's office and at the first relay of the neutral bank of relays at said way station when said line relay is energized by current of one polarity, and for causing simultaneous energization of the second relay of said dispatcher's office neutral bank and the second relay of the way

station neutral bank when said line relay is energized by current of the reverse polarity, and a plurality of channel circuits each including the same line wire and contacts of corresponding channel selecting relays of the dispatcher's relay bank and said way station relay bank.

15. In a synchronous selector train dispatching system; the combination with a stepping line wire, a message line wire and a common return wire; a compound group of relays at the dispatcher's office comprising groups of channel selecting relays and a bank of group selecting relays; a compound group of relays along the track way including groups of channel selecting relays and a bank of group selecting relays; means controlled over said stepping wire for causing the relays of said two banks of group selecting relays to operate sequentially in synchronism and for causing the relays of the selected groups of channel selecting relays to be operated sequentially and in synchronism; and wayside signals controlled over said message wire including front contacts of corresponding group selecting relays and front contacts of corresponding channel selecting relays.

16. In a synchronous selector train dispatching system; the combination with a stepping line wire, a message line wire and a common return wire; a plurality of direct current line relays connected in series in said stepping line wire; an alternating current relay connected in multiple with each direct current relay through a condenser, whereby said direct current relays and said alternating current relays may be controlled distinctively over said stepping line wire; synchronous selector means controlled by said alternating current relays; other synchronous selector means controlled by said direct current relays; and wayside signals controlled through channel circuits including contacts controlled by said first mentioned and said second mentioned synchronous selector means.

17. In a centralized traffic controlling system of the synchronous selector type, the combination with a control circuit and a message circuit, means at a central office for applying a plurality of distinctive currents to said control circuit, one relay for each distinctive current at a distant way station responsive only to such distinctive current, contacts at said way station in said message circuit closed when said relays assume their energized positions, contacts in said message circuit and at said dispatcher's office closed when said first mentioned contacts are closed, and means for transmitting a message current over said message circuit.

18. A centralized traffic controlling system for railroads comprising, a series of stepping relays interconnected so that they may be successively energized, a pick-up circuit

for each of said stepping relays including a front contact of the next preceding stepping relay and a back contact of the next succeeding stepping relay, a stick circuit for each stepping relay including a front contact of such stepping relay and back contact of the next succeeding stepping relay, and means for controlling said pick-up circuits.

19. A centralized traffic controlling system for railroads comprising, a series of stepping relays interconnected so that they may be successively energized, a pick-up circuit for each of said stepping relays including a front contact of the next preceding stepping relay and a back contact of the next succeeding stepping relay, a stick circuit for each stepping relay including a front contact of such stepping relay and back contact of the next succeeding stepping relay, and means for energizing said pick-up circuits one at a time.

20. A centralized traffic controlling system for railroads comprising, a series of stepping relays interconnected so that they may be successively energized, a pick-up circuit for each of said stepping relays including a front contact of the next preceding stepping relay and a back contact of the next succeeding stepping relay, a stick circuit for each stepping relay including a front contact of such stepping relay and back contact of the next succeeding stepping relay, and means for energizing the pick-up circuits of said stepping relays in successive order.

21. A centralized traffic controlling system for railroads comprising, a series of stepping relays interconnected so that they may be successively energized, a pick-up circuit for each of said stepping relays including a front contact of the next preceding stepping relay and a back contact of the next succeeding stepping relay, a stick circuit for each stepping relay including a front contact of such stepping relay and back contact of the next succeeding stepping relay, a line relay controlled from a distant point, contacts associated with said line relay which are alternately closed, one contact of said line relay included in the pick-up circuits of all odd stepping relays, and another contact of said line relay included in the pick-up circuits of all even stepping relays.

22. In a centralized traffic controlling system for railroads the combination with a line wire and a common return wire, line relays included in series in said line wire, a filter including an inductance and a condenser in series shunted around each line relay, other relays responsive to alternating current of a frequency which readily flows through said filters, and selector apparatus controlled by said line relays and said other relays.

23. In a centralized traffic controlling system for railroads the combination with a line wire and a common return wire, line re-

lays included in series in said line wire, a filter including an inductance and a condenser in series shunted around each line relay, other relays responsive to alternating current of a frequency which readily flows through said filters connected in multiple between said line wire and said common wire, and selector apparatus controlled by said line relays and said other relays.

24. In a centralized traffic controlling system for railroads the combination with a line wire and a common return wire, direct current polar relays included in series in said line wire, a filter including an inductance and a condenser in series shunted around each polar relay, other relays responsive to alternating current of a frequency which readily flows through said filters, and selector apparatus controlled by said polar relays and said other relays.

25. In a centralized traffic controlling system for railroads the combination with a line wire and a common return wire, direct current polar relays included in series in said line wire, a filter including an inductance and a condenser in series shunted around each polar relay, other relays responsive to alternating current of a frequency which readily flows through said filters connected in multiple between said line wire and said common wire, and selector apparatus controlled by said polar relays and said other relays.

26. In a centralized traffic controlling system for railroads the combination with a line wire and a common return wire, line relays included in series in said line wire, a filter including an inductance and a condenser in series shunted around each line relay, a plurality of way stations each having a line relay associated therewith, another relay located at each way station and responsive to alternating current of a frequency which will readily flow through said filter, a series of stepping relays at each way station each controlled by the associated line relay only when such particular way station has been selected, and way station selecting means for selecting one particular way station at one time controlled by said other relays.

27. In a centralized traffic controlling system for railroads the combination with a line wire and a common return wire, line relays included in series in said line wire, a filter including an inductance and a condenser in series shunted around each line relay, other relays responsive to alternating current of a frequency which readily flows through said filters connected in series with said filter, and selector apparatus controlled by said line relays and said other relays.

28. In a centralized traffic controlling system for railroads the combination with a line wire and a common return wire, direct current polar relays included in series in said

line wire, a filter including an inductance and a condenser in series shunted around each polar relay, other relays responsive to alternating current of a frequency which readily flows through said filters included in series with said filters, and selector apparatus controlled by said polar relays and said other relays.

29. In a centralized traffic controlling system for railroads the combination with a line wire and a common return wire, line relays included in series in said line wire, a filter including an inductance and a condenser in series shunted around each line relay, a plurality of way stations each having a line relay associated therewith, another relay located at each way station and responsive to alternating current of a frequency which will readily flow through said filter included in series with said filters, a series of stepping relays at each way station each controlled by the associated line relay only when such particular way station has been selected, and way station selecting means for selecting one particular way station at one time controlled by said another relays.

In testimony whereof I affix my signature.

OSCAR H. DICKE.

DISCLAIMER

1,795,084.—*Oscar H. Dicke*, Rochester, N. Y. TRAIN-DISPATCHING SYSTEM FOR RAILROADS. Patent dated March 3, 1931. Disclaimer filed February 16, 1934, by the assignee, *General Railway Signal Company*.

Hereby enters the following disclaimer:

1. Your petitioner hereby disclaims from claim 7 any system, except wherein the "station selecting means for selecting only one of said way station selectors" is controlled by alternating current.

2. Your petitioner hereby disclaims claim 11 which is in the following words, to wit:

"11. A synchronous selector of the counting relay type comprising; a line relay, a plurality of channel selecting relays arranged in order; a pick-up circuit for each odd numbered channel selecting relay including a front contact of the next preceding channel selecting relay, and a contact of said line relay closed when it assumes one extreme position; a pick-up circuit for each even numbered channel selecting relay including a front contact of the next preceding channel selecting relay, and a contact of said line relay closed when it assumes the other extreme position; and a stick circuit for each channel selecting relay including its own front contact and a contact opened upon the next change in the position of said line relay."

[*Official Gazette March 13, 1934.*]
